CIGAR MACHINE

Karl Erik Granstedt, Stockholm, Sweden, assignor to Aktiebolaget Formator, Stockholm, Sweden, a joint-stock company of Sweden

Application August 13, 1940, Serial No. 352,434
In Germany August 28, 1939

2 Claims. (Cl. 131—46)

This invention relates to cigar machines, and more particularly to such machines having a rolling table and an apron lying thereupon and being adapted to wind a tobacco filler into a tobacco leaf or binder, as in the operation of cigar bunching machines. In such machines the bunch rolling apron is operated by a bunch roller moving transversely into a position beyond the front end of the table, so as to cause part of the apron also to project beyond said front end of the table and eject the cigar or bunch. However, if a finished product is to be manufactured in such operation the tobacco leaf has to be pasted and the apron will be sticky, so that the cigar will adhere to the apron instead of being expelled therefrom.

It is an object of the invention to remove this drawback, so as to avoid any disturbance of the operation of the machine, and this is effected without injuring the cigar sticking to the apron. Another object of the invention is to provide means for protecting the apron from injuries otherwise likely to be caused when using cigar cutting means in the removal of the above-mentioned drawback.

In the drawings—

Fig. 1 is an elevational side view of one embodiment of the machine including the subject matter of the invention;

Fig. 2 is an elevational front view of the machine; and

Fig. 3 is an elevational side view on an enlarged scale of part of the machine.

A rolling table 2 is mounted on the machine frame 1 and supports a cigar rolling apron 3 the front end of which is secured to the machine frame below the front end 4 of the rolling table. A bunch roller 5 is movable transversely over the rolling table and actuates the apron 3 to wind a tobacco filler into a pasted binder placed in an outspread condition upon the apron. The wound product, viz., the cigar A, has to be expelled by the apron at the front end 4 of the rolling table, so as to drop into a receiver 6 when the bunch roller 5 has reached its foremost position, as shown in Fig. 3. Transfer means including a pair of carriers 8, having two sharp cutting edges 7, is positioned substantially below the receiver 6. The carriers 8 are movable upwards to transfer the expelled cigar from the receiver 6 to a receptacle 10. The ends of the cigar are cut in transit by the coaction of the cutter edges 7 of the carriers 8 and stationary cutters 9 which are laterally and vertically adjustably attached to standards 20 positioned on the machine frame 1.

The bunch roller 5 and the carriers 8 are driven

by a continuously revolving shaft 11. A cam disc 12 is secured to the shaft 11 and reciprocates a rod 13 which is pivotally connected to a lever arm 14 which is pivotally journaled on a shaft 15. 5 The upper, forked end of the lever arm 14 carries the bunch roller 5. Another cam disc 16 is secured to the shaft 11 and operates a lever 17 to which is pivoted one end of a link rod 18 the other end of which is pivoted to a short lever 19. The lever 19 is secured to a shaft 21 which is rotatably journaled in the brackets 20. Two other levers 22 are secured to the shaft 21, and each of them carries one of the cigar carriers 8, adjustably connected to them. To each of the carriers 8 is secured a rounded nose 23 which projects upwardly beyond the cutter edges. When elevating the carriers 8 the noses 23 will hit the lower side of the apron 3 between the roller 5 and the front end of the rolling table 2, so that the cutter edges 7 will never engage the apron. Thus the carriers 8 are first moved into the position close beneath the apron 3, as shown in Fig. 3. Thereafter, the bunch roller 5 is retracted, and by means of the rod 25 it retracts the forwardly projecting part of 10 the apron 3, so that the bunch retained by the noses 23 is swept off the apron and drops into the receiver 6. Thereafter, the carriers 8 are elevated further and swung forwards, whereby the cigar is transferred to the cutters 9 and further 15 to the collector 10. Instead of utilizing the rearward movement of the roller 5 and apron 3 to sweep off the cigar this can be effected by moving the carriers 8 forwardly before the roller 5 is retracted.

35 I claim:

1. In a cigar machine, a rolling table, a cigar rolling apron lying upon said table, means for periodically operating the apron to make part of said apron project beyond the front end of the rolling table, transfer means having a pair of cutting edges for cutting off the ends of the cigars, means for periodically moving said transfer means into a position close beneath said part of the apron, expeller members on said transfer 40 means having substantial extent in the direction transversely of the apron and provided with rounded portions projecting upwardly beyond said cutting edges so as to prevent engagement between said cutting edges and said apron, and means for relatively moving said expeller members and said part of the apron to cause said members to sweep off a cigar sticking to the lower side of said part of the apron.

2. In a cigar machine, a rolling table, a cigar 45 rolling apron lying upon said table, means for

periodically operating the apron to make part of said apron project beyond the front end of the rolling table, a pair of cutters having cutting edges for trimming the ends of the cigars, expelling members having rounded surfaces free of said cutters and extending upwardly beyond said cutters so as to prevent engagement between said cutters and said apron, said members also having substantial extent in the direction laterally of the direction of movement of the expeller members and being arranged at the insides of said cutters

and having bunch-engaging surfaces extending beyond said cutters and between the cutters, means for periodically moving said cutters to position said expelling members close beneath said part of said apron, and means for relatively moving said cutters and said part of the apron to cause said expelling members to sweep off a cigar sticking to the lower side of said part of the apron.
